A. M. BORNSTEIN

FELL GAUGE FOR LOOMS

Filed Sept. 24. 1923

WITNESS

Wm. M. Bell.

INVENTOR,
Abraham M. Bornstein,

John Deeward.
ATTORNEY.

UNITED STATES PATENT OFFICE.

ABRAHAM M. BORNSTEIN, OF PATERSON, NEW JERSEY.

FELL GAUGE FOR LOOMS.

Application filed September 24, 1923. Serial No. 664,577.

To all whom it may concern:

Be it known that I, ABRAHAM M. BORNSTEIN, citizen of the United States, residing at Paterson, in the county of Passaic and 5 State of New Jersey, have invented certain new and useful Improvements in Fell Gauges for Looms, of which the following is a specification.

This invention relates to fell gauges for 10 looms, that is to say, to fell gauges with reference to which the weaver, after the sheet of warp and finished fabric has been shifted longitudinally for any purpose, can reset such sheet to bring the fell of the 15 fabric accurately to its former position, so that on the weaving being proceeded with no blemish will appear in the goods, such as transverse marks due to too much spacing from or a crowding with respect to the fell 20 of the next ensuing pick of filling. One of the principal objects of the invention is to provide a loom with means whereby a fell gaging device will automatically take the gaging position upon stopping of the 25 loom and withdraw therefrom when the loom is again started so that it will be out of the way in the actual weaving.

In the drawing,

Fig. 1 is a top plan view of the front portion of a loom embodying my invention;

Fig. 2 is a plan of a fragment of the sheet of warp and finished fabric and of the fell gaging means and its support;

Fig. 3 is a front elevation of said means; 35 and

Fig. 4 is a side elevation thereof, the breast-beam appearing in section.

a is the breast-beam below which is arranged, as usual, a controller member for 40 controlling the driving of the loom, said member here consisting of a rock-shaft *b* journaled in the loom frame *c* and having a handle *b'*. The driving means and the mechanism through which it is actuated are 45 not shown because well known. When the controller member mentioned is in the "on" position, indicated by the solid-line position of its handle *b'* in Fig. 1, the loom will be driven, and when said member is in the 50 "off" position, indicated by the dotted-line position of said handle, the loom will be at standstill. *d* is the batten, adapted when the loom is driven to be reciprocated toward and from the breast-beam; *e* is the reed 55 thereon; and *f* the shuttle adapted to be

thrown across the batten by any well-known means.

On the breast-beam is secured by two screws *g* or otherwise an elongated plate *h* which preferably has two spaced depending 60 rests *h'*, so that it stands a little above the top surface of the breast-beam. This plate extends lengthwise of the breast-beam and is arranged near the controller *b'*.

On the plate, which preferably reaches a 65 trifle over the line coincident with the nearer margin of the fabric *A*, and near its inner end is an upstanding screw *i* affording a fulcrum for a lever structure which may be described as follows: In the form shown 70 this lever structure is angular, having one arm in the form of a bar *j* having a longitudinal slot *j'* receiving the screw *i* (so that the lever structure has a sliding fulcrum on the screw) and at its inner end an extension stud *j''* on which is pivoted, so as to be movable in a vertical plane, the other arm which comprises a socket *k* having the 75 actual pivotal bearing on the stud and a stem *l* which is telescoped into the socket 80 and may be adjusted lengthwise by manipulating a set-screw *m*, the stem terminating in a blade *l'* whose free end edge is perpendicular to the stem.

On the plate near its outer end is another 85 screw *n* which affords a fulcrum for a lever *o* which is here a straight bar. Its outer end is adapted to be held normally in the path of movement of the controller, i. e., of its handle *b'*, by a spring *p* which connects 90 the lever with the frame of the loom. The limit of movement of the lever under the pull of the spring is afforded by a pivoting knife-joint connection *q* (between its inner end and the adjoining end of bar *j*) adapted 95 in folding to present its salient angle toward the batten.

On the plate, near its inner end, is an upstanding cam *r* the function of which will appear in the following description of the 100 operation of the mechanism:

When the loom is started running, by shifting the controller handle to the full-line position in Fig. 1, said handle shifts the lever *o* to the oblique position shown in this 105 figure, which in turn shifts the mentioned lever structure also to the oblique position there shown, its blade *l'* being retracted from the fell *C* of the fabric and out of the way for weaving. When the lever structure is 110

thus shifted its pivoted arm wipes over the cam *r* and is elevated so that its free end stands clear of and so cannot bear on and thus produce any possible blemishing of the fabric. When the loom is stopped, by shifting the controller handle to the dotted-line position in Fig. 1, the spring *p* returns lever *o* and consequently the lever structure to the limit afforded by the knife-joint connection *q* (or so that the bars *j* and *o* are alined). This brings the free end edge of the blade *l'* coincident with the true line of the fell and should the weaver have any occasion for moving the sheet of warp *B* and fabric *A* he can on resetting the same obtain perfect accuracy as to coincidence of the fell with its former position by using the free end edge of said blade as a gauge; this is insured partly because the lever structure is now held against a definite stop (afforded by contact at the knife-joint connection by the end of bar *j* with the end of bar *o*) and partly because in this position of the parts the pivoted arm of the lever structure has cleared the cam *r*, allowing said blade to lie upon the fabric.

Having thus fully described my invention, what I claim and desire to secure by Letters Patent is:

- 30 1. A loom including supporting means and a system of movable parts arranged therein and including a controller for controlling the starting and stopping of the loom movable back and forth from one to the other of the "on" and "off" positions and vice versa and fell-gaging means confined to move with the controller back and forth out of and into fell-gaging relation to the fell-line.
- 40 2. A loom including supporting means and a system of movable parts arranged therein and including a controller for controlling the starting and stopping of the loom movable back and forth from one to the other of the "on" and "off" positions and vice versa and fell-gaging means confined to move with the controller back and forth and horizontally out of and into fell-gaging relation to the fell-line.
- 50 3. A loom including supporting means

and a system of movable parts arranged therein and including a controller for controlling the starting and stopping of the loom movable back and forth in an upright plane from one to the other of the "on" and "off" positions and vice versa and fell-gaging means confined to move with the controller back and forth and horizontally out of and into fell-gaging relation to the fell-line.

4. A loom including supporting means, fell-gaging means movable in the supporting means substantially horizontally from one to the other of positions where it will be in or out of fell-gaging relation to the fell-line and normally held in one of said positions, and a controller for controlling the starting and stopping of the loom movable from one to the other of the "on" and "off" positions and vice versa and arranged when moved to one of its said positions to shift the gaging means from one to the other of the said positions thereof.

5. A loom including supporting means, fell-gaging means movable in the supporting means substantially horizontally from one to the other of positions where it will be in or out of fell-gaging relation to the fell-line and normally held in one of said positions, and a controller for controlling the starting and stopping of the loom having a part thereof movable in an upright plane from one to the other of the "on" and "off" positions and vice versa and arranged when moved to one of its said positions to shift the gaging means from one to the other of the said positions thereof.

6. A loom including supporting means, a fell-gaging means movable back and forth in the supporting means in a plane facing that of the sheet of fabric and warp and into and out of gaging relation to said sheet, said fell-gaging means including a gaging member movable into and out of contact with said sheet, and means to cause said movement of said member when said fell-gaging means is moved back and forth.

In testimony whereof I affix my signature.

ABRAHAM M. BORNSTEIN.
